UNITED STATES PATENT OFFICE

133,316

DESIGN FOR A COMBINATION TRAILER HEARSE AND AMBULANCE OR SIMILAR ARTICLE

James R. Jordan, Jr., Bedford, Va.

Application August 30, 1941, Serial No. 103,119

Term of patent 14 years

To all whom it may concern:

Be it known that I, James R. Jordan, Jr., residing at Bedford, in the county of Bedford and State of Virginia, have invented a new, original, and ornamental Design for a Combination Trailer Hearse and Ambulance or Similar Article, of which the following is a specification, reference being had to the accompanying drawing, forming part thereof.

Figure 1 is a side elevational view of a combination trailer hearse and ambulance or similar article, showing my new design.

Figure 2 is a front elevational view thereof, and

Figure 3 is a rear elevational view thereof.

The opposite side is a duplicate of that shown in Figure 1.

I claim:

The ornamental design for a combination trailer hearse and ambulance or similar article, as shown and described.

JAMES R. JORDAN, JR.
